(57) CLAIM

The ornamental design for a paper box as shown and described.

DESCRIPTION

FIG. 1 is a front, top perspective view of a first embodiment of the paper box, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the paper box, shown in an unfolded configuration;

FIG. 10 is a front, top perspective view of a second embodiment of the paper box;

FIG. 11 is a rear, bottom perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof; and,

FIG. 18 is another perspective view of the paper box, shown in an unfolded configuration.

1 Claim, 18 Drawing Sheets
